UNITED STATES PATENT OFFICE.

HENRY CSANYI, OF ORANGE, NEW JERSEY.

ELECTRIC HORN.

No. 851,655.

Specification of Letters Patent.

Patented April 30, 1907.

Application filed June 28, 1906. Serial No. 323,961.

To all whom it may concern:

Be it known that I, HENRY CSANYI, a subject of the King of Hungary, and a resident of Orange, Essex county, New Jersey, have invented certain new and useful Improvements in Electric Horns, of which the following is a specification.

My invention relates to electric horns to be used for signaling purposes, for instance on automobiles.

The object of my invention is to provide a very simple and efficient device of the above-indicated class.

Reference is to be had to the accompanying drawings in which

Figure 1 is a longitudinal section, (on line 1—1 of Fig. 2) of a horn embodying my invention, and Fig. 2 is a top view thereof, with parts broken away.

A is the casing of the horn, preferably provided with openings A' in its rear end wall. Into the open front end of this casing is fitted the cylindrical flange B' of the funnel-shaped mouth-piece B from which the sound issues. This flange may be held simply by friction, or it may be more securely fastened by soldering or otherwise. Within the casing is located a U-shaped arm or carrier C, the ends of which as shown may come up on the inside of the flange B' and be secured thereto by screws D the heads of which are received in notches A² at the forward edge of the casing A. Within the cover or mouth-piece B a metal ring E is arranged, with washers F, and a diaphragm G between the washers. Screws H secure the ring, washers and diaphragm together, but these screws should not touch the diaphragm, so that the latter will be insulated by the washers F. The diaphragm carries a spring I adapted to form a circuit-breaker in conjunction with a screw J on the mouth-piece B or other stationary part of the apparatus. An armature K is also attached to the diaphragm G, and faces the poles of the electro-magnet L, secured to the carrier C. The wire coils of the electro-magnet are connected at one end with the diaphragm, as shown at G', and at the other end with a binding screw M, carried by the back of the casing A, but insulated therefrom. The terminals of the battery or other source of electric current are connected with the screws J and M respectively. The wire shown attached to the screw J might be fastened instead to a binding screw on the back of the casing A.

In operation, as the current is turned on by means of a suitable switch of any approved style, the current would energize the electro-magnet L, thus attracting the armature K. 60 This brings the diaphragm G toward the electro-magnet but does not at once interrupt the contact between the spring I and the screw J, the spring being normally under tension. Only when the armature K has moved inward a predetermined distance, the spring I will come out of contact with the screw J so as to break the circuit. The moment this happens, the magnet L will no longer attract the armature and the diaphragm will swing 70 back whereby the circuit is again closed, and this operation is repeated in quick succession.

The vibrations of the diaphragm G produce a sound which is condensed and conveyed to the outside by the tapering mouth-piece B. The apertures A' of the casing are provided in order to allow the air within the casing to freely respond to the vibrations of the diaphragm, since a body of inclosed air would tend to damp the vibrations. The 80 use of a spring contact in connection with the diaphragm enables me to secure a much more reliable action than if the screw B engaged the diaphragm directly.

The apparatus might operate without the 85 use of a separate armature K if the diaphragm is made of a magnetic material, but even when such material is used for the diaphragm, I prefer to secure a separate armature thereto, thus attaining a more efficient 90 action.

I claim:

1. An electric horn comprising a casing with apertures in its rear end, a tapering mouth-piece at the front end of said casing, a 95 U-shaped carrier located within the casing, an electro-magnet supported by said carrier, a diaphragm located between said electro-magnet and the outlet of the mouth-piece, a spring carried by the diaphragm on the outlet side thereof, an armature carried by the opposite side of the diaphragm, a contact screw adapted to engage said spring, and electrical connections for causing the circuit of the electro-magnet to be closed and broken 105 as the diaphragm vibrates under the influence of the electro-magnet.

2. An electric horn comprising a casing provided with an outlet for the escape of sound, an electro-magnet within said casing, 110 a diaphragm located between the outlet and the electro-magnet, a spring carried by the

diaphragm, a contact member engaging the spring, and electrical connections to close and break the circuit of the electro-magnet as the diaphragm vibrates.

- 5 3. An electric horn comprising a casing having an outlet for the escape of sound, an electro-magnet within said casing, a diaphragm between the outlet and the electro-magnet, an armature and a spring carried by said diaphragm, a contact member engaging the spring, and electrical connections for causing the circuit of the electro-magnet to be closed and broken as the diaphragm vibrates.
- 10 4. An electric horn comprising a casing provided with an outlet for the escape of sound, an electro-magnet in said casing, a

diaphragm located between the said outlet and the electro-magnet, an armature secured to the diaphragm on the side facing the electro-magnet, a spring secured to the diaphragm on the opposite side, a contact member engaging said spring, a connection from one end of the armature coils to the diaphragm, and a binding screw connected with the other end of the electro-magnet coils.

In testimony whereof, I have hereunto signed my name in the presence of two subscribing witnesses.

HENRY CSANYI.
